INVENTOR
ROGER G. WILLIAMS,

BY ## UNITED STATES PATENT OFFICE

1,996,315

INDICATOR

Roger G. Williams, Okmulgee, Okla., assignor of
one-half to William H. Hancock, Okmulgee,
Okla.

Application May 26, 1934, Serial No. 727,786

6 Claims. (Cl. 40—65)

This invention relates to indicators and more particularly to a price indicating device especially adapted for use by gasoline station attendants.

An important feature of the invention resides in the provision of a device for accurately indicating the total price of gasoline purchases at given rates per gallon, thereby avoiding the need of mental computation on the part of the attendant or operator.

Another important feature of the invention is to provide an indicating device of exceedingly compact construction which may be conveniently carried on the person of the attendant or which may be located on the cash register or on the desk of a person checking sales tickets.

A further aim is to provide a price indicating device in which there will be found means for supporting and displaying a plurality of strips bearing price indications of gasoline figured at current or prevailing prices per gallon, in conjunction with which there is provided a storage space or compartment for the reception of additional strips bearing price indications for gasoline at other prices per gallon affording means by which those strips bearing the price indications for gasoline at current or prevailing prices may be conveniently arranged for display or use while the remaining strips are packed away in the storage space therefor protecting the same against wear, loss or being soiled.

Other objects and advantages of the invention will be apparent during the course of the following description.

In the accompanying drawing forming a part of this application and in which like numerals designate like parts throughout the same,

Figure 1 is a perspective view of the indicator,

Figure 2 is a similar view with the chart carrier or holder partially withdrawn from the casing,

Figure 3 is a group perspective of the device,

Figure 4 is a transverse sectional view through the device,

Figures 5, 6 and 7 are fragmentary perspective views of the chart holder illustrating modified forms of the price strip and strip accommodating groove.

In the drawing, the numeral 5 generally designates a substantially rectangular casing adapted to slidably and removably receive through the open upper end thereof a similarly shaped chart holder or carrier 6.

Except when the indicator is actually being employed in calculating a given quantity of gasoline or the like, the chart holder 6 occupies the

fully telescoped position within the casing 5 shown in Figure 1 so that the over-all dimensions of the indicator will be such as to allow the same to be conveniently carried in the pocket of the gasoline station attendant or to be placed near the cash register of the gas station.

As shown in Figures 1 and 2, the front wall of the casing 5 is in the nature of a rectangular frame having narrow sides and ends providing a window 7 of relatively generous proportions and across which window there is extended a transparent enclosure or pane 8. Obviously, this arrangement affords a view of the chart carried by the member 6 and prevents the chart from being soiled while being carried in the pocket or hands of a gasoline station attendant.

As clearly illustrated in Figure 3, the chart holder 6 is of hollow construction having the front wall thereof provided with a plurality of longitudinally extending, spaced, parallel elements or ribs 9 co-operating to define a plurality of longitudinally extending strip receiving grooves 10. As shown, the elements 9 are formed integral with the front wall of the holder 6, but it is, of course, understood that these elements may be separate elements secured to the front wall of the holder in any preferred manner.

The grooves 10 are adapted to removably and selectively receive relatively narrow price indicating strips 15, each one of which is adapted for use in determining the price of gasoline purchases at a given price per gallon. That is to say, there will be one strip for gasoline at seventeen cents a gallon, another strip for gasoline at eighteen cents a gallon and so on through the entire range of prices that prevail from time to time.

For the purpose of neatness and ease of operation, the strips 15 will be found to completely fill the grooves 10 with the outer faces of the strips 40 flush with the outer faces of the ribs 9.

It is believed to be clear that the strips 15 may be formed from celluloid or other material found suitable for the purpose and either or both sides of the strips may bear columns of numbers 20 for use in indicating the total price of one or more gallons of gasoline at given rates per gallon either with or without the tax or other extra charges.

For cooperation with the price indications on the strips 15, the two intermediate elements or ribs 9 are provided with columns of gallon designating numbers 25 which are spaced to correspond with the spacing of the numbers 20 on the price indicating strips 15 so that the gallon 55

indicating numbers will be in transverse alignment with the price indicating numbers on the associated strips 15.

By providing several of the ribs 9 with gallon indicating numbers or columns of numbers, there is located immediately next to each of the several price indicating strips gallon indicating means thereby providing for the rapid calculation of the total price of a given number of 10 gallons of gasoline.

As is well known, the price of gasoline is constantly changing or fluctuating and for this reason it is necessary to have conveniently at hand a number of price indicating strips 15 for use 15 with current prices. To provide for this, the holder 6 is of hollow construction to produce a storage compartment or space 30 accommodating a number of price indicating strips. Thus, it will be seen that a large number of price indicating 20 strips are carried within the device itself and are readily accessible for use when the occasion arises by simply withdrawing the holder from the casing 5.

It is clearly shown in Figures 1, 2 and 3 that 25 what might be said to be the outer end member 35 extends beyond the ends and sides of the body of the holder 6 for convenient manual engagement for the purpose of sliding or moving the holder with respect to the casing 5 and at 30 the same time to close the outer ends or to form stops for the outer ends of the grooves 10 providing a simple means by which outward endwise movement of the various price indicating strips is limited.

With further reference to the means by which 35 the several price indicating strips are held in place, it is pointed out that in addition to being snugly received in the grooves 10, such strips have the outer faces thereof flatly against the transparent member 8 so that there can be no lateral or outward displacement of such strips.

In carrying out the invention it is intended 40 that the chart carrier or holder 6 shall have a snug sliding fit within the casing 5, one that is responsive only to manual movement of the members 5 and 6 with respect to each other, and by 45 reference to Figure 2 it will be seen that the opposite side walls of the chart holder 6 are provided between the edges thereof with lugs or protuberances 40 adapted to be received in complementary 50 sockets or recesses 41 in the opposed walls of the casing 5 when the parts occupy the position shown in Figure 1. From this it will be seen that when the parts 40 and 41 are in interfitting 55 relation, such parts cooperate with the frictional contact between the telescoping members 5 and 6 in holding the last mentioned members against shifting one with respect to the other.

In use, the indicator may be carried on the 60 person of a gasoline station attendant or conveniently mounted on a cash register or other support and when it is desired to determine the price of a given number of gallons of gasoline it is merely necessary to draw the holder 6 outwardly until the number of gallons purchased, 65 for example, eight gallons appearing on the ribs 9 comes in line with the outer end of the casing 5.

With the quantity indicating number thus brought into line with the outer straight edge or 70 end of the casing 5, the operator has only to glance along that same line where there will be found an indication of the price of the purchase being made, with the result that the attendant is relieved of the necessity of the mental calculation of the price by a process of multiplication.

With the purchase price thus determined it is simply necessary to return the chart holder 6 to the position shown in Figure 1 to allow the entire article to be conveniently carried upon the person.

It will also be apparent that, if desired, the operator may determine the price of a given number of gallons of gasoline by simply holding the device in one hand, with the parts in the position shown in Figure 1, and moving the thumb 10 of the same hand or the index finger of the other hand into line with the desired gallon and price indications.

It is a simple matter to substitute for the strips mounted in the grooves 10 of the holder 6 those 15 adapted for use in connection with gasoline at current prices, it being observed that the lower end of the holder 6 is fully open for the reception and removal of those price indicating strips not of immediate use. In this connection, it might 20 be pointed out that since the storage space is open at the lower end and such lower end is located within the casing 5, there is prevented the accidental loss of the strips.

In Figure 5 there is shown a modified form of 25 price indicating strip 50 having its opposite longitudinal edges rounded or transversely curved for engagement with the correspondingly shaped side walls of the groove 52 to provide an interlocking connection between the strip 50 and the 30 chart carrier 54 permitting endwise movement of the strip.

In the form of invention illustrated in Figure 6 35 the opposite longitudinal edge of the strip 60 and the opposite side walls of the groove 62 are dovetailed so as to hold the strip in position in the groove and at the same time permit the strip to be conveniently moved endwise when it becomes necessary to do so.

Figure 7 illustrates another form of strip and 40 groove wherein there is a tongue and groove connection between the strip 70 and the side walls of the groove 72.

Having thus described the invention what is 45 claimed is:

1. In an indicator for determining the price of purchases of gasoline by the gallons, a casing having one end thereof open and provided with a straight edge forming an indicating line, a chart holder snugly and slidably mounted in said casing and being provided with a plurality of spaced, longitudinally extending grooves and intervening ribs, certain of said ribs being provided with numbers arranged in columns and consecutively to indicate gallons of gasoline, and strips detachably and slidably mounted in said grooves and bearing price indications for given numbers of gallons of gasoline and being located in transverse alignment with the corresponding numbers on said ribs, said holder being provided with means for manual engagement to position said gallon and price indicating numbers in line with said straight edge of the casing.

2. In an indicating device of the character described, a casing having an open end and a front wall provided with a window, a chart carrier movably mounted in said casing through the open end thereof, said chart carrier being provided with a front wall having a plurality of spaced, longitudinally extending grooves, price 70 indicating strips removably mounted in said grooves, each of said strips being provided with numbers indicating the price of a given number of gallons of gasoline at a given rate per gallon, said carrier bearing gallon designations co- 75

operating with the price indicating numbers on said strips, said gallon designations and price indicating numbers being visible through said window.

5. 3. In an indicating device of the character described, a casing having an open end and a front wall provided with a window, a chart carrier movably mounted in said casing through the open end thereof, said chart carrier being provided 10 with a front wall having a plurality of spaced, longitudinally extending grooves, price indicating strips removably mounted in said grooves, each of said strips bearing price designations for a given number of gallons of gasoline at a given 15 rate per gallon, said carrier bearing gallon designations cooperating with the price designations on said strips, said gallon and price designations being visible through said window, said carrier being of hollow construction and having 20 an open lower end to provide a storage space for additional price indicating strips.

4. In an indicator for determining the price of purchases of gasoline by the gallons, a casing having one end thereof open and provided with 25 a straight edge forming an indicating line, a chart holder detachably and slidably mounted in said casing and being provided with a plurality of spaced, longitudinally extending grooves and intervening ribs, certain of said ribs bearing gallon 30 designations, and strips detachably mounted in said grooves, each of said strips bearing price designations for given numbers of gallons of gasoline at a given rate per gallon and adapted for cooperation with said gallon designations on

said ribs, said holder being provided with means for manual engagement to position said gallon and price designations in line with said straight edge of said casing, said holder being of hollow construction and having an open lower end to provide a storage space for additional price indicating strips.

5. In an indicator for determining the price of purchases of gasoline by the gallons, a chart holder having a plurality of spaced, longitudinally extending grooves, and price indicating strips detachably mounted in said grooves, each of said strips bearing price designations for a given number of gallons of gasoline at a given rate per gallon, said holder bearing gallon designations 15 cooperating with the price designations of said strips, said holder being of hollow construction to provide a storage space for additional price indicating strips.

6. In an indicator for determining the price 20 of purchases of gasoline by the gallons, a chart holder having a plurality of spaced, longitudinally extending grooves and intervening ribs, price indicating strips detachably mounted in said grooves, each of said strips bearing price designations for a given number of gallons of gasoline at a given rate per gallon, there being an interlocking connection between each of said strips and said grooves, certain of said ribs being provided with gallon designations cooperating with the 25 price designations of said strips, said holder being of hollow construction to provide a storage space for additional price indicating strips.
